SCREEN ELECTROPHOTOGRAPHIC CHARGE
INDUCTION PROCESS

The invention relates to improvements in or relating to an electrophotographic process, and more particularly, to novel means for preparation of an electrostatic latent image on a record member, and also to a radiation sensitive member which is subjected to imagewise exposure to an original to be reproduced and conveys image information to the final record member. The invention also relates to intermediate and final record members for use with such process.

The known electrophotographic process such as Xerography or Electrofax employs a layer of photoconductive material which is uniformly charged in darkness by corona discharge and then exposed imagewise to form an electrostatic latent image thereon. The latent image is developed by a toner, and the Electrofax process fixes the developed image on the photoconductive layer, while in the Xerography, the developed image is transferred onto an image receiving member to be fixed thereon. Usual photoconductive layer used in the Xerography comprises a deposited film of amorphous selenium and the residue of toner which remains unremoved on the selenium film during the transfer must be cleaned to ensure satisfactory operation of the film when used repeatedly. However, the film surface is susceptible to damage by the cleaning operation owing to abrasion by toner powder and cleaner brush, thereby causing a degradation in the image quality. There have been several proposals which avoid such disadvantage by transferring an electrostatic latent image on the selenium film directly onto an insulating record member before the image is developed, as disclosed in U.S. Pat. No. 2,982,647. Alternatively, an electrostatic latent image is formed on an insulating record member while holding it at a very small distance of air gap from a photoconductive member during imagewise exposure with a voltage being applied simultaneously across the both members, as disclosed in U.S. Pat. Nos. 2,825,214, 2,833,648 and 2,937,943 issued to L.E. Walcup. However, these approaches involve technical difficulties in maintaining a constant and uniform air gap between the members and are dissatisfaction in their commercial utility.

Therefore, it is an object of the invention to provide an improved electrophotographic process and apparatus for preparation of an electrostatic latent image on a final record member which is technically readily feasible and lends itself to continuous recording with good image quality.

It is another object of the invention to provide a novel radiation sensitive member which serves to convey image information from an original to a final record member in the form of an electrostatic latent image.

Fundamentally, according to the invention, the electrophotographic process of forming an electrostatic latent image on an insulating record member held in contact with another member while a voltage is being applied thereacross is characterized in that one or the other of the members has a thin insulating layer of a mesh pattern on its surface, which abuts against the other or said one of the members.

In one aspect, the process according to the invention employs a radiation sensitive member comprising a radiation sensitive layer on which is formed an insulating layer of a mesh pattern. The term radiation sensitive layer is intended herein to mean a normally electrically insulating layer which obtains an increased electrical conductivity upon exposure to radiation of any suitable wavelength, including corpuscular ray and X-ray. Usually such layer may comprise a suitable known photoconductive material when light is chosen as a carrier of image information. Where X-ray is used as the image carrier, a deposited film of amorphous selenium may be used as such layer. A record member of an insulating material is held against the mesh layer of the radiation sensitive member and a voltage is applied across the both members for a short period during which the composite is exposed to radiation image of an original to be reproduced. This forms an electrostatic latent image of the original on the insulating record member, which image is developed and fixed subsequent to separation of the record member from the radiation sensitive member.

Alternatively, the radiation sensitive member may be initially formed with a latent image thereon by a separate process which may comprise any conventional means. The member is then placed in close contact with a final record member, and then a voltage is applied between the both members. Transfer of the latent image occurs from the radiation sensitive member to the record member by migration of electric charges through the spaces defined by the patterned dots of the mesh layer.

Preferably, the radiation sensitive member comprises a substrate having sufficient mechanical strength to withstand the pressure with which an insulating record member is pressed thereagainst. The substrate may be either insulative or conductive and when it is insulative, it should have a conductive surface commensurate in area with the radiation sensitive layer. The radiation sensitive layer may form an ohmic contact with the substrate, or a barrier which prevents injection of free charge carrier may be formed between the layer and the substrate. In the former case, the time constant, τ , when charge is being supplied to the surface of the radiation sensitive layer by dark current is given by

$$\tau = \kappa_s \epsilon_0 \rho, \quad (1)$$

where κ_s denotes dielectric constant of the layer material, ϵ_0 permittivity in vacuum and ρ resistivity of the layer material when not exposed to radiation, which may be referred to hereinafter as dark resistivity. When both the radiation sensitive member and the insulating record member are exposed to imagewise radiation while in contact, the time period of voltage application required for the formation of the latent image must be at least equal to the exposure time, t_0 , thus

$$\tau \geq t_0 \quad (2)$$

The time t_0 depends on the sensitivity of the radiation sensitive layer and the intensity of radiation used. For example, when a deposited film of amorphous selenium is used with a light source which comprises a tungsten incandescent lamp providing illumination of 100 luxes on the surface of the selenium film, t_0 will be 0.2 second. Thus, in this instance, $\rho \geq 3 \times 10^{11} \Omega \text{ cm}$. Amorphous selenium usually has a ρ -value of the order of $10^{15} \Omega \text{ cm}$. and hence is suitable for the purpose of the invention.

When a barrier is formed between the radiation sensitive layer and the conductive substrate which prevents injection of free charge carrier, the density of charge, σ , induced on the layer surface by application of the voltage will be given by

$$\sigma = n l_s e, \quad (3)$$

where n denotes the concentration of free charge carriers in the layer, l_s the layer thickness and e the charge of a charge carrier. Assuming uniform distribution of donors or acceptors in the layer, the reverse electromotive force or polarization voltage caused by induced charges will be as follows:

$$V_p = \frac{l_d K_d + Z}{D + Z} \cdot \frac{n e}{2 K_s \epsilon_0} l_s^2, \quad (4)$$

where l_d and K_d denote the thickness and dielectric constant of a record member, respectively, Z the length of air gap provided by the pattern dots between the both members and D is given by the following equation:

$$D = l_s / \kappa_s + l_d / \kappa_d \quad (5)$$

The maximum permissible value of V_p depends upon various factors, but for the purpose of illustration, it will be assumed here to be 100 v. and when other parameters assume the following values:

$$l_d / \kappa_d = 3 \text{ microns}$$

$$l_s / \kappa_s = 10 \text{ microns}$$

$$l_s = 63 \text{ microns}$$

$$Z = 10 \text{ microns}$$

then the permissible concentration of charge carrier will have to be

$$n \leq 3 \times 10^{13} \text{ cm}^{-3}$$

Using this figure, the dark resistivity, ρ , of a radiation sensitive layer having mobility μ of $1 \text{ cm}^2/\text{v.sec}$. is calculated to be

$$\rho = 2 \times 10^8 \Omega \text{ cm}.$$

which is nearly 10^{-8} times less than the necessary value in an ohmic contact system. In practice, however, there will be no contact which constitutes a potential barrier capable of completely suppressing injection of charge carrier. Thus the possibility of a small leakage current, I_d , must be catered for which builds up a potential on the surface of the radiation sensitive layer. The charge accumulation is proportional to the time period of voltage application, and placing the resulting voltage equal to V_p , given by the equation (4), we have,

$$I_d = (\kappa_s \epsilon_0 / l_s) \cdot (V_p / t_0) \quad (6)$$

Assuming $V_p = 100$ v., $\kappa_s / l_s = 10^3$ cm.⁻¹ and $t_0 = 0.2$ second,
 $I_d = 5 \times 10^{-8}$ A.

This is the value below which the leakage current of the radiation sensitive layer must be held.

When the radiation sensitive layer is formed with a latent image before it is held in pressed relationship with a record member, the time length from the formation of a latent image on the radiation sensitive layer until completion of transfer will be greater, that is, the factor t_0 will be by about ten to hundred times greater than before, so that it is required that the dark resistivity be greater and the leakage current be smaller at corresponding proportions.

The process mentioned above depends for its operation upon the migration of electric charge to the surface of a record member in those parts of the space defined by the dots of the mesh layer which correspond to irradiated parts of the radiation sensitive member. This requires the application of a sufficiently high voltage, which in turn necessitates to ensure good insulation of the mesh layer. Experiments have shown that the mesh layer should have a resistivity not less than 10^9 Ω cm. and a surface resistance not less than 10Ω per square. The thickness of the mesh layer determines the length of the air gap between the radiation sensitive layer and the record member, and in order to ensure good image quality of the latent image, the thickness should be within a range from 0.5 to 100 microns, preferably from 5 to 20 microns. Additional requirements imposed upon the material of the mesh layer are that it is highly adherent to the surface of the radiation sensitive layer, that it does not exhibit any aggressive behavior to the surface to cause degradation of its characteristics and that it has sufficient mechanical strength and durability to withstand repeated use.

Such mesh layer may be formed in various ways. In one example, a photopolymerizable material e.g. photoresist available from Eastman Kodak Company under the trademark of KPR or KMER is applied on a radiation sensitive layer to a thickness given above. After drying, it is exposed to ultraviolet ray through a mask of suitable pattern and unilluminated parts are removed by a developer principally comprising trichlene. After drying, the remaining photoresist is fixed. This provides a meshwork of very high resolution. Alternatively, conventional electrophotographic process proposed by Carlson may be used to form an electrostatic latent image of desired pattern on a radiation sensitive layer, and the latent image may be developed by an insulating toner and fixed. In this instance, the thickness can be controlled by the intensity of charge provided by corona discharge or by the intensity of exposure. Typical materials for the mesh layer includes polyethylene, polystyrene, polyester, polyamide, Teflon (trademark), vinyl chloride, vinyl acetate, phenol resin and co-polymers of these materials.

Where the mesh layer has a poor adherence to the underlying radiation sensitive layer or when it is desired to prevent any reaction with the latter, a substratum may be provided on the radiation sensitive layer. When the substratum has a thickness not less than 0.5 micron, and up to 10% thick of the radiation sensitive layer, it is found that the provision of such substratum has no substantial influence upon the image quality. As known, such substratum may also serve to reduce mechanical abrasion of the radiation sensitive layer.

As mentioned previously, the dark resistivity required for a radiation sensitive layer can be reduced by several orders by providing a thin insulating layer, between the conductive sub-

strate and the radiation sensitive layer, which prevents injection of charge carrier. The leakage current through such thin layer must be held below the value estimated by the equation (6) and its thickness should be chosen so as not to degrade the contrast of the image, which would be satisfied when the thickness is below about 10% of that of the radiation sensitive layer. In addition, the radiation sensitive layer may comprise more than one layers to increase the quantum efficiency during the formation of the latent image.

10 In another aspect, the process according to the invention employs a final record member which has on its insulating recording layer an insulating layer of a mesh pattern. The mesh layer may be similarly constructed as that of the radiation sensitive member described above. In addition, the insulating recording layer and the mesh layer may be formed integrally. The thickness and resistivities of the mesh layer are similar to those indicated previously. In this instance, the formation of an electrostatic latent image on the record member 15 is effected by using a radiation sensitive member having a radiation sensitive layer supported on a substrate, the layer being pressed against the mesh layer of the record member. The major difference from the first mentioned process is that the radiation sensitive member used in this instance does not 20 have a mesh layer, which is transposed onto the final record member.

Such mesh layer of the record member may be formed in various ways, and the techniques described above in connection with the preparation of the radiation sensitive member 30 may be used. Alternatively, a copperplate of desired pattern and depth is prepared and is filled with a copperplate ink for printing on a recording layer. Such copperplate ink comprises a non-colored transparent solution which becomes electrically

35 insulating upon drying and solidification, such for example as a transparent resin solution of relatively low viscosity. Excessive ink attaching to the surface of the copperplate is doctored off. When the recording layer and the mesh layer are formed as integral, a thermoplastic resin such as polystyrene is coated

40 on a support or formed into a single-layered film as by extrusion or casting technique and pressed against a heated matrix which is previously formed on a metal roll in a desired pattern and with a desired depth. Upon removal of the resin film from the matrix, the resin film will have a mesh-shaped unevenness

45 formed on its surface. In this operation, suitable choice of the roll temperature, pressing time or the relative speed between the roll and the film is important. To facilitate detachment of the film, it is preferred to shape the matrix so as to provide tapering dots in the form of truncated cone or pyramid. Application of higher fatty acids such as stearic acid, as a remover, 50 on the matrix surface may be effectively used.

In a further aspect, the process according to the invention employs an intermediate record member which comprises an insulating recording layer on which is formed another insulating layer of a mesh pattern. The construction, material and sizes of the intermediate record member may be same as the record member described just above in connection with the second process. When preparing an electrostatic latent image 55 on a final record member according to this process, the intermediate record member is held pressed against a radiation sensitive member in the first step, the radiation sensitive member used in this process comprising a radiation sensitive layer on which no mesh layer is formed. In the second step, the intermediate record member is held in close contact with a final record member. In each of the first and second steps, a high voltage is applied between the respective two members held in contact to effect transfer of a latent image from one to another. Imagewise exposure is effected in the first step simultaneously with the application of the voltage.

60 In all of the processes described above, it is essential for best results to ensure a close and uniform contact between mating members with proper spacing provided by patterned dots. Suitable means therefor will be described later with reference 65 to various embodiments.

For better understanding of the invention, it will be described in more detail with reference to the drawings, in which

FIG. 1 is a schematic section to an enlarged scale of a novel radiation sensitive member according to the invention,

FIG. 2 is a similar view of a modification of the member shown in FIG. 1,

FIG. 3 shows various patterns of the mesh layer,

FIG. 4 is a schematic view illustrating the process of the invention using a radiation sensitive member with a mesh layer,

FIG. 5 is a similar view where the radiation sensitive member is not, but the record member is transparent to radiation,

FIGS. 6a to 6c show the process in which a latent image is formed on the radiation sensitive member prior to its contact with the record member,

FIGS. 7a and 7b show the process in which a positive is obtained,

FIG. 8 is a schematic view of a copying machine in which the process shown in FIG. 4 is employed,

FIGS. 9a to 9d are sections of various forms of a record member used in the second manner of the process according to the invention,

FIG. 10 is a schematic view illustrating the process using the record member shown in FIG. 9,

FIG. 11 is a view schematically illustrating a preferred manner of ensuring good contact between a radiation sensitive member and a record member,

FIGS. 12a and 12b show the process using the record member of FIG. 9 in which a positive is obtained,

FIG. 13a to 13c show another manner of the process using the record member of FIG. 9 in which a positive is obtained,

FIG. 14a to 14d are schematic sections of an intermediate record member used in accordance with the third aspect of the process according to the invention,

FIGS. 15a and 15b show a manner of carrying out the process for formation of an electrostatic latent image on a final record member using the intermediate record member shown in FIG. 14,

FIGS. 16a to 16d show another manner of the process with the intermediate record member of FIG. 14, and

FIGS. 17 to 21 show various forms of a copying machine incorporating the intermediate record member of FIG. 14.

Referring first to FIGS. 1 to 8 inclusively, which show the radiation sensitive member proposed by the invention and processes and apparatus which use the member, this member is generally shown in FIG. 1 by reference numeral 1 and includes a conductive substrate 2, and a radiation sensitive layer 3 as defined above which is evaporated on the substrate or coated thereon in the form of a dispersion in resinous binder. On the layer 3 is secured an insulating layer 4 which has a mesh pattern as shown in FIG. 3. In FIG. 3, black portions may represent an insulating material and white portions spaces therebetween or vice versa, and the pattern may comprise any regular or irregular array of dots, lines, solid triangles, diamonds or the like which can represent a picture element. Usual halftone or crossline screen pattern widely used in the art of printing may be suitable for the pattern of the insulating layer 4. Preparation and useful thickness of such mesh layer has been mentioned previously. The radiation sensitive member shown in FIG. 2 is generally similar to that of FIG. 1 except that the substrate 2 is of an insulating material and has a conductive thin film 2' deposited thereon to provide an electrode.

Referring to FIG. 4, the process of forming an electrostatic latent image on a record member 5 with using the above radiation sensitive member 1 will be described. The record member 5 comprises an insulating recording layer 6 on a conductive base 7, but the record member may be a commercially available electrostatic recording sheet. As shown, both the members 1 and 5 are positioned on a counterelectrode 8, with the mesh layer 4 abutting against the insulating recording layer 6. Suitable pressure in the order of from 0.1 to 1 kg./cm.² is applied

between the substrate 2 and the electrode 8 to cause a close and uniform contact between the both members. The electrodes 2', 8 are connected to a DC source 9 through a switch 10 and are also interconnected by another switch 11. In the example shown, it is assumed that the substrate 2 and conductive film 2' are both transparent to radiation 12 which is used for the imagewise exposure. Such substrate and electrode can be formed with Nesa glass, for example.

Upon closure of the switch 10, a high tension is applied across the electrodes 2', 8, and as the assembly is exposed to radiation 12, free charge carriers, electrons or positive holes, created by irradiation move to the surface of the layer 3 under the influence of the electric field, so that there is produced a very strong field in the space between the layers 3 and 6. For this reason, there occurs migration of electric charge to the layer 6 through the air space left between the land or mesh material 4, so that there will be provided electric charge on the surface portions of the recording layer 6 which face the air space in the mesh layer 4 in the region exposed to radiation 12. Then switch 10 is opened followed by closure of switch 11, which short-circuits the members. Subsequently the record member 5 is separated from the member 1 and the latent image thereon is developed and fixed. The density of such surface charge on the recording layer 6 has a tendency to increase with an increasing amount of exposure, but saturates at a value which depends on the film thickness and dielectric constant of the layers, the characteristics of the radiation sensitive layer, the magnitude and polarity of the voltage applied and other factors. However, excessive exposure is objectionable because of spread or blur of a resulting image. The polarity of the voltage may be arbitrarily determined in most cases, but a particular polarity may be sometimes preferred depending upon the kind of the radiation sensitive material used. The optimum value of the voltage applied depends upon the thickness and dielectric constant of various layers, and an example will be given below.

Amorphous selenium was deposited on a Nesa glass to a film thickness of 50 microns and a mesh layer 10 microns thick of KPR was provided on the film. A record member comprised a film of Mylar 12.5 microns thick having a deposited aluminium film. These members were pressed together and to the surface of Nesa glass was applied a voltage of -1,120 volts. After irradiation of a light image for one second with maximum illumination of 20 luxes on the image surface, the Nesa glass surface and the deposited aluminium film were short-circuited. Then the record member was separated from the Nesa glass and the latent image on the Mylar film surface was developed with a magnetic brush. The developed image had satisfactory image quality.

It is to be noted that synchronization of the exposure with the application of the voltage, though preferred, is not essential in the manner of operation shown in FIG. 4. It is sufficient to provide exposure during application of the voltage. However, the exposure time concurrent with the voltage application is the effective exposure period, which must be long enough to form an electrostatic latent image on the record member.

A suitable insulating record member 5 may be formed by providing an insulating recording layer on a flexible conductive support, such as a so-called electrostatic recording sheet which comprises a thin insulating recording layer applied on a paper which has been treated to be conductive. Also it may comprise a flexible insulating material provided with a thin conductive coating on one surface thereof, e.g. polyester film with deposited metal such as aluminium; a transparent insulating material with a transparent conductive layer which may comprise SnO_2 , TiO_2 , CuI or the like; or a film of insulating resin alone, whether transparent or opaque, which has resistivity and surface resistance sufficiently high to retain an electrostatic charge, for example, polyethylene, polystyrene, polyester, polyamide, Teflon (trademark), vinyl chloride, vinyl acetate, phenol resin or the like. Thus the record member 5 can be constituted by a single layer of an insulating

material, which preferably is flexible to ensure good contact with the radiation sensitive member.

It will be appreciated that both the radiation sensitive member 1 (except mesh layer 4) and the record member 5 are not completely plane, but include surface roughness and undulations so that such unevenness causes irregularities in the degree of close contact between these member particularly when the electrode 8 comprises a rigid material such as metal, thereby resulting in the degradation of image quality. Such disadvantage can be eliminated by using the electrode 8 which is made from a soft, elastic material. Such soft, elastic electrode 8 should have sufficient thickness and deformability to compensate for the surface roughness and undulations. A conductive rubber sheet 1 cm. thick proved satisfactory for this purpose. When such soft, elastic electrode 8 is used, it is desirable to provide a support on the back of the electrode 8 for the convenience of applying pressure and such support can be formed from metals or plastics material of relatively high strength such as bakelite.

FIG. 5 shows another manner of the above process which is employed with a radiation sensitive member having an opaque conductive substrate. In this instance, a record member 5 consists of a transparent insulating film 6, e.g. a film of polyester resin, and a transparent conductive film 7 such as copper iodide. The electrode 8 is constituted by a transparent conductive material and is supported on a transparent substrate 8' which may be formed with Nesa glass. Radiation 12 is applied through the transparent layers 6 to 8 and 8'. The operation of the process is the same as in FIG. 4.

The radiation sensitive member 1 may be previously formed with an electrostatic latent image before being placed in contact with the record member 5. An example of such manner of operation is illustrated in FIGS. 6a to 6c, where like parts are designated by same reference numerals, but the electrode 8 is replaced by a roller and the switch 10 is a double pole-double throw switch rather than a single pole switch as in FIGS. 4 and 5. Also for the sake of brevity, the insulating mesh layer 4 is shown in continuous lines, but it should be noted that it is formed in a pattern as shown in FIG. 3. Initially the switch 10 is thrown to the position shown in FIG. 6a, and the roller 8 is moved from left to right while rolling, thereby providing a high negative potential to the conductive substrate 2 and providing a positive charge to the lower surface of the radiation sensitive layer 3 through the air space in the mesh layer 4. Then the member 1 is exposed to imagewise radiation 12 (FIG. 6b), thereby forming an electrostatic latent image thereon. Now the member 1 is superimposed on a record member 5. The switch 10 is thrown to the other position as shown in FIG. 6c, and the supply voltage is applied across the conductive substrate 2 and the roller electrode 8 with the substrate 2 positive (FIG. 6c). As the roller 8 is moved from left to right while pressing the record member 5 against the radiation sensitive member 1, the latent image is transferred from the latter to the recording layer 6. Then the switch 11 is closed to remove charge from the member 5 and the two members 1, 5 are separated from each other.

Another manner of forming a latent image on the radiation sensitive member 1 prior to its contact with a record member is shown in FIGS. 7a and 7b. Here, the member 1 has a transparent substrate 2 and a transparent conductive layer 2', as shown in FIG. 2, and initially a negative potential is applied to the electrode layer 2' with respect to the roller electrode 8, which is moved from left to right, as shown. However, in this instance, there is provided a light shield 13 having a slit 14 above the member 1. The light shield is arranged to be slidable in a plane parallel to the member 1, and as the roller 8 moves to the right, the light shield 13 also moves in the same direction at the same speed. During such movement of the roller 8 and light shield 13, the member 1 is exposed imagewise to radiation 12 through the moving slit 14. Thus negative charges will be produced on the surface of the radiation sensitive layer 3 not covered by the patterned mesh layer 4. Then the radiation sensitive member 1 having a latent

image thus formed thereon is superimposed on a record member 5 (FIG. 7b), and while applying the voltage, the roller 8 is again moved from left to right to urge the record member 5 against the radiation sensitive member 1, whereupon the latent image is transferred onto the insulating recording layer 6.

While in the above embodiments, charges are produced on the recording layer 6 at positions subjected to radiation 12 so that the image developed will be a negative, it is possible in FIG. 7b to reverse the polarity of the voltage applied to obtain a positive.

Several examples of the above process and radiation sensitive member will be given below, which however should not be construed as limitation to the invention.

EXAMPLE 1

A substrate was prepared by using a hard glass 2 mm. thick to deposit thereon a thin film of tin oxide, which is usually called a Nesa film. On the Nesa film was applied an evaporated film of amorphous selenium to a thickness of 50 microns. An 8 micron thick layer of KPR was formed as a mesh layer on the selenium film. The meshwork comprised thin flat discs of KPR having a diameter of about 50 microns which were arranged in a regular form with spacing of about 75 microns, providing 200 meshes. This constituted a radiation sensitive member. Such member was used together with a commercially available electrostatic recording sheet in the process generally similar to that illustrated in FIG. 4. The urging electrode used was a conductive rubber sheet having a thickness of 1 cm. and hardness of 30 (JIS), and pressure of about 1 kg./cm.² was applied to press the radiation sensitive member and the record member together. Applying +750 volts to the conductive Nesa film and using an exposure of 20 lux·sec. from a photographic enlarger, a latent image of good image quality was obtained.

EXAMPLE 2

On the same Nesa glass substrate as used in Example 1 was applied a thin film, about 2 microns thick, of thermosetting epoxy resin and on the resin film was coated a mixture, in equal volume proportions, of fine powder of cadmium sulfide activated by copper and thermosetting silicone resin as binder. A mesh layer 10 microns thick was prepared on the coating in the similar manner as in Example 1, using Dycril, photopolymerizable resin available from Du Pont Company. Using a radiation sensitive member thus formed and a commercially available electrostatic recording sheet in the similar process as in Example 1, with the voltage of -1,200 volts and exposure of 5 lux·sec., a latent image of good image quality was obtained.

EXAMPLE 3

On one surface of a 1 mm. thick aluminum plate was formed an alumina film having a thickness of 500 Å. by plasma oxidation technique. On the alumina film was provided the coating of cadmium sulfide-silicone resin dispersion, used in Example 2, to a thickness of 50 microns. After setting of the coating, a KPR mesh layer, 8 microns thick and 200 meshes, was applied thereon, thus completing a radiation sensitive member. This member was used in the process illustrated in FIGS. 6a to 6c. The voltage used in the step of FIG. 6a was -1,500 volts, the exposure in FIG. 6b was 5 lux·sec., and the voltage applied in the step of FIG. 6c was +900 volts. The roller speed was 20 cm./sec. and the urging force of 10 kg. weight was used. The latent image obtained showed good image quality.

EXAMPLE 4

On the same Nesa glass substrate as used in Example 2 was applied an epoxy resin layer about 2 microns thick on which was evaporated crystalline selenium to a thickness of 1 micron followed by further evaporation of amorphous selenium to a

thickness of 50 microns. On the surface of the latter was applied a mesh layer of KPR, 8 microns thick and 200 meshes as in Example 1. The radiation sensitive member thus formed was used in the similar process as in Example 1 and provided a latent image of good image quality, but the exposure required was 5 lux-sec., showing that the present radiation sensitive member had four times as high a sensitivity as that of Example 1.

EXAMPLE 5

On an aluminium plate 1 mm. thick was evaporated a layer of amorphous selenium to a thickness of 100 microns and on the selenium layer was applied a mesh layer of KPR 10 microns thick. This radiation sensitive member was used in the process illustrated in FIG. 4, but using the conductive rubber electrode as in Example 1. A pressure of 1 kg./cm.² was applied to the electrode. The exposure to an X-ray image of maximum dosage rate 450 mr./sec. for one second during application of +1,200 volts produced an electrostatic latent image of good quality. The record member used in Examples 3 to 5 were commercially available electrostatic recording sheets, and the latent image was developed with a magnetic brush.

FIG. 8 shows a copying machine which is constructed to carry out the process illustrated above. The machine includes a stationary light source such as a lamp 20, which serves projection of the image of a transparent original 21 through an optical system 22 and a slit 23 in a fixed light shield 24 onto a radiation sensitive member 25. The member 25 includes a transparent conductive substrate which is earthed as shown and its radiation sensitive or photoconductive layer is disposed to face a continuous web of record member 26 as the latter is moved past a conductive rubber electrode 27, the record member 26 being supplied from a roll 28 through a pair of guide rollers 29. The member 25 is arranged slidably horizontally as indicated by a both-ended arrow, and the arrangement is such that as the original 21 is moved to the left, as viewed in this Figure, at a constant speed, the members 25, 26 are moved to the right at the same speed as the speed of the focussed image, so that the image of successive parts of the original 21 is focussed on the corresponding contiguous parts of the record member 26. The roller electrode 27 is made from conductive rubber and is rotatably carried on a vertically movable support 30. A DC source 31 has its one terminal connected with a finger 32 which contacts the roller surface for application of a suitable voltage, and the other terminal of the source is earthed. Suitable means is provided, though not shown, to maintain a tension in the record member 26 and to drive it, when necessary, past the roller 27, guide rollers 33, 34, a developer unit 35 and a fixing unit 36 to a take-up spool 37.

In operation, before the original is set in motion to move one frame of the original below the lamp 20, the support 30 is raised upward to cause the roller 27 to urge the record member 26 against the photoconductive layer or move precisely the mesh layer of the radiation sensitive member 25, and as the original starts to move, both the members 25 and 26 are fed to the right at the same speed as the original. The lamp and the source are turned on, and then an electrostatic latent image is formed on the record member 26. Upon termination of the motion of the original by a distance of one frame, the forward drive is interrupted for a period, and the support 30 is lowered to release the record member 26 from contact with the member 25, which is then allowed to return to its initial position. Then the machine is ready for another copying cycle. The latent image on the record member 26 is developed and fixed before the latter is taken up on the spool 37.

As mentioned previously, the process according to the invention is operable with a record member which includes on its insulating recording layer a mesh layer of the kind specified above. Such record member is shown in FIGS. 9a to 9d, and FIGS. 10 to 13 inclusively show the manners of the process using such record member.

Referring to FIG. 9a, such record member is generally shown at 50 and consists of an insulating layer 51 adapted for use as a record carrier and another insulating layer 52 of a mesh pattern as indicated in FIG. 3. The material for such mesh layer 52 as well as its thickness and electrical properties should be similar to those described with reference to the mesh layer of the radiation sensitive member shown in FIGS. 1 and 2. However, the layers 51 and 52 may be formed with same material and hence integrally as shown in FIG. 9b, where 10 the record member 50 includes a conductive layer 53. The record member shown in FIG. 9c has a substrate 53 which may be electrically conductive or insulating. Numeral 54 denotes a substratum which prevents penetration of a solvent that is used when coating the insulating recording layer 51 on the substrate. Such substratum may be formed by using a water soluble resin such as polyvinyl alcohol or any other suitable material that is insoluble to the solvent used for the coating of the recording layer. Such substratum can be omitted in certain 15 circumstances depending upon the nature of the substrate material and the coating technique used. FIG. 9d shows a modification of FIG. 9c where the layers 51 and 52 are integral. Suitable material for the recording layer 51 includes polyethylene, polystyrene, polyester, vinyl acetate, phenol 20 resins or their copolymers, and the choice will be made from consideration of charge retention, film plasticity, flexibility, surface characteristics, compatibility with coating, economic factors or the like. The recording layers in FIGS. 9c and 9d need not be transparent, but they may comprise a dispersion 25 of fine white powder such as titanium or zinc oxide in any of above resins. However, the record member 50 having the mesh layer must have sufficient flexibility to ensure the formation of a uniform latent image. Flexibility found in commercially available electrostatic recording papers is satisfactory.

FIG. 10 shows a manner of the process of forming a latent image on a record member 50 of the type shown in FIG. 9c, and numerals 8 to 12 denote parts designated by corresponding numerals in FIGS. 4 and 5. For the convenience of description, it is assumed here that light is used as radiation 12. Then 30 a photoconductive member 55 is used which comprises an integral lamination of a transparent substrate 56, a transparent conductive layer 57 and a photoconductive layer 58, which may be of similar material as used in Carlson process. The member 55 is placed on the member 50 with the photoconductive layer 58 abutting against the mesh layer 52, and the composite is positioned on an electrode 8. Suitable means (not shown) is used to press the both members together with a pressure of from 0.1 to 1 kg./cm.², for example. The conductive layer 57 is connected through switch 10 to the positive 35 terminal of a DC source 9, of which negative terminal is connected to the electrode 8. In addition, the electrode 8 and the layer 57 are interconnected through a switch 11. When the switch 10 is closed and radiation 12 is released imagewise, there will be produced positive charges on the surface of the 40 photoconductive layer 58, opposite to the insulating recording layer 51, where subjected to the exposure. Such surface charges produce an electric field of sufficient strength to cause migration of charge to the layer 51, thereby forming an electrostatic latent image on the surface of the recording layer 45 51. Upon termination of the exposure, the switch 10 is opened and the switch 11 is closed to short-circuit the layer 57 and the electrode 8. Then the both members 50 and 55 are separated and the latent image on the recording layer 51 is developed.

The electrode 8 may be constituted by a soft, elastic material such as conductive rubber and a separate pressure plate 55 may be urged against the back of the electrode in order to apply pressure, thereby ensuring close and uniform contact between the both members. The record member shown in FIGS. 9a and 9b may be equally employed in above process.

FIG. 11 shows a convenient method of assuring a close contact between the members. The record member 50 having a mesh layer and the photoconductive or radiation sensitive member 55 are disposed horizontally in superimposed relationship. The member 50 comprises transparent materials entirely and its conductive layer 53 is connected with one ter-

55 minal of a DC source 9 through a switch 10. The member 55 has a conductive substrate 56 which is connected with the other terminal of the source. In this particular arrangement, the member 55 has a radiation sensitive layer 58 of such size and configuration that leaves a free marginal area of the conductive substrate 56 all around the radiation sensitive layer 58. The both members are covered by an air-tight and transparent film 60, such as Mylar film, which is sealed at its opposite ends and side edges with the conductive substrate 56 by suitable means indicated at 61. In an end part of the conductive substrate 56 is formed an opening 62, which is connected to a suction means such as vacuum pump. The space enclosed by the film 60 is partly evacuated, for example, to 0.8 atm., and such sub-atmospheric pressure serves to achieve a close and uniform contact between the both members 50, 55. Then the switch 10 is closed and radiation 12 is released. It is to be noted that while high vacuum is favourable to make the contact closer, it renders the charge migration through the air space between the both members difficult to occur, thereby requiring a higher voltage for the source 9.

In FIGS. 10 and 11, there will be an electric charge in the irradiated parts of the record member and therefore such charge provides a negative when developed. However, the process illustrated in FIGS. 12a and 12b provides a positive. In these Figures, the radiation sensitive member 55 totally comprises transparent materials and the electrode 8 is in the form of a roller. In addition, the switch 10 is a double-pole double-throw switch. Initially, a negative potential is applied to the conductive layer 57 of the radiation sensitive member 55 from the DC source 9 and at the same time the assembly 50, 55 is exposed to uniform radiation from the side of the member 55. During such exposure, the roller 8 is moved from left to right while rolling to press together successive parts of the members 50, 55 (FIG. 12a). This step charges the record member 50 uniformly. Then the roller 8 is returned to the left, and a light shield 63 having a slit 64 is arranged above the assembly in parallel thereto (FIG. 12b). The switch 10 is thrown to the other position and thus a positive potential is applied to the conductive layer 57. Then the radiation 12 which is defined imagewise is released and the roller 8 is moved to the right as before. Simultaneously, the light shield 63 is moved to the right at the same speed as the roller 8 to scan the whole area of the member 55. The transfer of charge occurs again, which charge this time is positive and hence neutralize the charge which exists already on the record member. The neutralization occurs imagewise so that the remaining charge on the record member will conform in pattern to the original. In other words, the electrostatic latent image on the record member 50, when developed, provides a positive.

In the process using a record member having a mesh layer, the radiation sensitive member may also be formed with a latent image previously, that is, before it is placed in contact with the record member. Such manner of operation is schematically shown in FIGS. 13a to 13c. Initially, a corona charger 65 is connected with a DC source 9' of high voltage and is moved over the radiation sensitive layer 58 of a radiation sensitive member 55 (FIG. 13a). The conductive substrate of the member is earthed as is the negative terminal of the source. The layer 58 is uniformly charged positive. Then, FIG. 13b, the member 55 is exposed imagewise to radiation 12, whereby the charge in the irradiated areas will disappear. Subsequently, the member 55 is superimposed with a record member 50 of the form shown in FIG. 9d and the both members are pressed together by using an electrode 8 of soft, elastic conductive material and a backing support 8'. When switch 10 is closed to apply a positive potential to the member 55 (FIG. 13c), the latent image thereon is transferred to the record member. Upon opening switch 10, switch 11 is closed and then the member 55 is removed. Development of the resulting latent image on the record member provides a positive.

Several examples of a record member shown in FIG. 9 and the process using such member will be given below.

EXAMPLE 6

On a 50 micron thick paper of high quality was coated a substratum of polyvinyl alcohol to a thickness of 5 microns and on the substratum was coated a film of polystyrene resin 10 microns thick. The resulting composite is equivalent to a commercially available electrostatic recording paper. On the resin film was applied an insulating mesh layer, 8 microns thick, of polyvinyl butyral resin, using the copperplate printing technique mentioned previously. The copperplate ink comprised a 20% resin solution in alcohol. On the other hand, a photosensitive member was prepared by coating a conductive film of tin oxide, or Nesa film, on one surface of a hard glass plate 2 mm. thick, and by evaporating a 50 micron thick film of amorphous selenium on the conductive film. The both members were used in the process shown in FIG. 10, using a voltage of +750 volts and an exposure for a quarter of a second to a light output from a photographic enlarging device providing maximum illumination of 80 luxes on the image surface. The image on the record member was satisfactory.

EXAMPLE 7

On a paper of high quality, 50 microns thick, was coated a substratum of polyvinyl alcohol, 5 microns thick, and on the substratum was coated a 12 micron thick film of polystyrene resin. On the surface of the resin film was formed a mesh layer using the heated roll technique, thereby obtaining a record member of the form shown in FIG. 9d. The meshwork was 200 meshes and individual dots were in the form of a truncated cone having a height of 8 microns, top diameter of about 40 microns and bottom diameter of about 50 microns. This record member was used together with the photosensitive member described in Example 6 in the process shown in FIG. 10 with the alternative that the electrode 8 comprised a conductive rubber sheet of 1 cm. in thickness and having hardness of 30 (JIS). Applying a pressure of 500 gr./cm.² to the rubber sheet and using a voltage of +750 volts and exposure for one second to a photographic enlarging device which provides maximum illumination of 20 luxes on the image surface, an image of good quality was obtained.

EXAMPLE 8

On a 12.5 micron thick film of polyethylene terephthalate (Mylar) was coated photoresist KPR available from Eastman Kodak Company to a thickness of 8 microns. A meshwork of 200 meshes was held in contact with the photoresist layer and the latter was exposed to ultraviolet ray. A developer comprising principally trichlene was applied to the photoresist to dissolve those parts which had not been polymerized, thereby obtaining a record member of the form shown in FIG. 9a. The record member was used in the same process as in Example 7 and provided a latent image of good quality.

EXAMPLE 9

A polystyrene film of 30 microns in thickness was tensioned on a rubber-lined drum of 50 cm. in diameter, and a roller matrix made from copper and having a diameter of 10 cm. and heated to 110° C. was held against the polystyrene film under pressure. Rotating the drum at a peripheral speed of 3 m./min., dots of 8 microns in height and 200 meshes were formed in the surface of the polystyrene film. The film was removed from the drum and on its back was applied a 1 micron thick layer of copper iodide, thereby forming a record member of the form shown in FIG. 9b. On the other hand, a photoconductive member was prepared by evaporating amorphous selenium to a thickness of 50 microns on an aluminium plate 2 mm. thick. The record member and radiation sensitive member thus prepared were used in the process illustrated in FIG. 11 with the inner space enclosed by the film 60 being evacuated to 0.8 atm. Applying +1,500 volts to the record member and using an exposure for one second to a photographic enlarging device providing maximum illumination of 20 luxes on the image surface, a satisfactory latent image was obtained.

EXAMPLE 10

Using the same record member and radiation sensitive member as described in Example 7 in the process illustrated in FIGS. 12a and 12b, an electrostatic latent image of good quality was obtained. The voltage used in the step shown in FIG. 12a was -750 volts and the illumination was 200 luxes on the surface of the radiation sensitive member. The roller 8 comprised conductive rubber of hardness 30 (JIS) and had a diameter of 4 cm. A force of 10 kg. weight was applied to the roller while it was being moved to the right at a speed of 5 cm./sec. In the step shown in FIG. 12b, the voltage applied was +750 volts. The slit had a width of 0.5 cm., and the exposure was to a photographic enlarging device providing maximum illumination of 100 luxes on the image surface. The roller speed and pressure remained unchanged.

EXAMPLE 11

A radiation sensitive member was prepared by evaporating amorphous selenium to a thickness of 50 microns on an aluminum plate 1 mm. thick. This member was subjected to the steps shown in FIGS. 13a and 13b. Initially, a tungsten wire of 0.08 mm. in diameter was connected with a DC source of +6,000 volts and was moved from left to right at a speed of 5 cm./sec. over the selenium layer of the member, thereby charging it by corona discharge. In the step of FIG. 13b, a photographic enlarging device was used to provide an exposure to the member for one second and with maximum illumination of 20 luxes. In the step of FIG. 13c, a record member described in Example 7 was used to transfer the image, using a voltage of +750 volts. The image obtained was satisfactory.

In above Examples, a latent image obtained was examined by development with known liquid developer.

FIGS. 14 to 21 illustrates further aspect of the process according to the invention in which an intermediate record member is used to form an electrostatic latent image on a final record member or image receiving member. This process includes at least two steps, the first one being formation of a latent image on the intermediate record member and the second being transfer of the latent image from the latter to the final record member.

Various forms of the intermediate record member which can be used in the present process are shown in FIGS. 14a to 14d. In FIG. 14a, an intermediate record member 70 is shown to include an insulating recording layer 71 and another insulating layer 72 of a mesh pattern shown in FIG. 3. The material and thickness of the mesh layer 72 may be similar to those described with reference to that of the radiation sensitive member 1 shown in FIGS. 1 and 2 or the record member 50 shown in FIGS. 9a to 9d. The material for the insulating recording layer 71 may be similar to that described in connection with the recording layer 51 shown in FIGS. 9a to 9d. In addition, the insulating layers 71 and 72 may be formed integrally as shown in FIG. 14b, where numeral 73 denotes a conductive layer applied to the bottom of the recording layer 71. Furthermore, where the material of the recording layer 71 has an insufficient mechanical strength, the member 70 as illustrated in FIG. 14b may be strengthened by a backing support or substrate 74 of a conductive or insulating material, which may comprise paper, natural or synthetic resin film, cellulose film, or woven textile of resin, cellulose or glass fibers. Obviously the layer 73 can be omitted when the substrate 74 is conductive. When the substrate 74 is formed from paper, woven textile or cloth, it may be desirable to provide a substratum 75 between the conductive layer 73 and the substrate 74 in order to prevent a solvent that is used when coating the recording layer 71 from penetrating into the substrate 74 and to eliminate any influence of unevenness of the substrate material upon the surface profile of the recording layer 71. In the example shown in FIG. 14d, the substrate 74 is non-conductive and thus the conductive layer 73 is applied on the surface of the substratum. However, when the substrate is conductive, there is no need to provide such layer 73.

It will be understood that the construction of the intermediate record member 70 is generally similar to the record member 50 shown in FIGS. 9a to 9d. However, because the member 70 is not a final image receiving member, it may be of any color. Further, the substrate 74 must have sufficient mechanical strength to allow repeated use. The mesh layer 72 and the recording layer 71 may be prepared in any manners mentioned above, including the photoresist technique, the copperplate technique and the heated matrix roll technique.

A manner of operating the process with the intermediate record member 70 is shown in FIGS. 15a and 15b, where numerals 9 to 12 denote corresponding parts illustrated in FIG. 4 or FIG. 10. The process employs a radiation sensitive member of similar construction as illustrated in FIG. 10 and for the convenience of description, such member is designated by same reference numeral 55 as in FIG. 10. Thus the member 55 comprises a substrate 56, a conductive layer 57 and a photoconductive layer 58, the substrate and the conductive layer being transparent in this example. Initially, the members 55 and 70 are placed in contact with the photoconductive layer 58 abutting against the mesh layer 72 of the intermediate record member 70, and using a conductive electrode plate 8, such as made from conductive rubber sheet, and a backing support 8', the members 55 and 70 are pressed together to achieve a close and uniform contact therebetween (FIG. 15a). Then closure of the switch 10 and energization of imagewise radiation 12 produce an electrostatic latent image on the recording layer 71 by a process as described with reference to FIGS. 4 and 10. Then the switch 11 is closed, and subsequently the radiation sensitive member 55 is removed from contact with the intermediate record member 70 and replaced by a final record member 76 which may be of similar construction as that used in the process shown in FIG. 4. Such final record member may be of any conventional form which may comprise a conductive base 77 and an insulating recording layer 78 as shown, or may comprise an insulating layer 78 alone. Such record member 76 and the intermediate record member 70 having the latent image formed thereon are placed in superimposed relationship with the insulating layer 78 contacting the mesh layer and are held sandwiched between a pair of conductive rubber electrodes 8, which in turn are pressed toward each other by a pair of backing plates 8' (FIG. 15b). Then the switch 10 is closed again to apply a positive potential to the upper electrode 8. Since the latent image on the intermediate record member 70 is formed such that positive charges remain on the insulating layer 71 in areas opposite to the irradiated areas of the photoconductive member 55 during the initial step, the field intensity in the air space provided by the pattern dots of the mesh layer will be less in those areas of the layer 71 having the positive charges than other areas, and there will be migration of negative charges to the surface of the layer 78 except those areas facing the positively charged or image areas of the layer 71. The net result of this is that the insulating recording layer 78 of the final record member 76 will have a latent image which is a positive of the original. It will be understood that a negative can be obtained on the final record member by reversing the polarity of the voltage applied in either step. However, it should be noted that the voltage applied in the first step must sometimes be limited to either polarity depending upon the nature of the radiation sensitive member used. The voltage value depends upon the thickness of the photoconductive or radiation sensitive layer of the member 55 and the thickness of the recording layers of both the intermediate and final record members 70, 76 as well as the thickness of the mesh layer 72. Thus voltages in the two steps may be different and so it is desirable to provide an adjustable voltage source 9. In FIG. 15a, the switch 11 may be replaced by a resistor R which is connected in the position shown in broken lines. The purpose of such resistor R is the same as the switch 11, that is, to remove charge from the radiation sensitive member 55. It will be understood that such resistor may be used also in FIGS. 4, 5 and 11 to substitute for the switch 11. Such resistor or closure of the switch 11 is

necessary prior to separation of the both members, since otherwise the retained charge on the radiation sensitive member causes a spark to occur as the separation increases. However, in certain circumstances, depending upon the values of source voltage and thickness of the mesh layer, it is possible to maintain the switch 10 closed when the both members are separated.

FIGS. 16a to 16d illustrates another manner of operation of the process using the intermediate record member 70, in which known Carlson process is used to form an initial latent image on a radiation sensitive member 55. FIGS. 16a to 16c are generally similar to FIGS. 13a to 13c except that the final record member 50 is replaced by the intermediate record member 70. Thus the radiation sensitive member 55 is uniformly charged (FIG. 16a), exposed imagewise to radiation 12 (FIG. 16b) and held in contact with the intermediate record member 70 under pressure, and the application of the source voltage 9 across the members effect transfer of a latent image on the member 55 (FIG. 16b) onto the intermediate record member 70 (FIG. 16c). Then the radiation sensitive member 55 is removed and replaced by a final record member 76, whereupon the procedure described with reference to FIG. 15b is repeated to transfer the latent image on the intermediate record member 70 to the final record member 76. The final image obtained on the member 76 is a negative in the example shown, but the polarity of the voltage applied in the step of either FIG. 16c or FIG. 16d may be reversed to provide a positive on the final record member 76.

It is emphasized again that the presence of the mesh layer is essential to satisfactory formation of a latent image and to good reproducibility of such process.

While transparent substrate and conductive materials are used for the radiation sensitive member in FIGS. 15a and 15b, the member in FIGS. 16a to 16c may not be transparent and may comprise a photoconductive layer on a metal plate such as aluminum, and thus a photoconductive plate used in the Carlson process may be used. In the process of FIG. 16d, an elastic electrode 8 was used, but with most final record member 76 which is flexible, the upper or lower electrode may be a metal electrode.

Several examples of the intermediate record member and process therewith will be given below.

EXAMPLE 12

On a 2 mm. thick hard glass substrate was deposited a thin conductive film of tin oxide to provide a Nesa glass plate, on which was evaporated amorphous selenium to a thickness of 50 microns. This constitutes a photoconductive member. An intermediate record member of the form shown in FIG. 14a was prepared by using a 25 micron thick film of polyethylene terephthalate (Mylar) as a recording layer and applying thereon a mesh layer of KPR 8 microns thick and 200 meshes, with individual dots having a diameter of 50 microns. A commercially available electrostatic recording paper was used together with these members in a process illustrated in FIGS. 15a and 15b. In the initial step, a voltage of +1,080 volts was applied to the photoconductive member, using a photographic enlarging device to provide an exposure for one second with maximum illumination of 20 luxes on the image surface. In the second step, a voltage of +1,170 volts was applied to the upper electrode 8. An electrostatic latent image of good quality was obtained on the recording paper.

EXAMPLE 13

An intermediate record member of the form similar to that shown in FIG. 14d was prepared by using a paper support having a conductive film on one surface. On the other surface of the paper was coated a 5 micron thick substratum with polyvinyl alcohol and on the substratum was coated a film of polystyrene to a thickness of 30 microns. Using the heated matrix technique, a mesh layer of 200 meshes was formed in the surface of the polystyrene film. The dots were of truncated

conical form having top diameter of 40 microns and bottom diameter of 50 microns with height of 8 microns. This member was used together with a photoconductive member of Example 1 and a commercially available electrostatic recording paper in the process shown in FIG. 15. Applying a voltage of +1,100 volts to the photoconductive member in the initial step and using the same exposure as in Example 12, and applying a voltage of +1,170 volts to the upper electrode 8, a latent image of good quality was obtained on the recording paper.

EXAMPLE 14

On an aluminium plate 2 mm. thick was evaporated a layer of amorphous selenium to a thickness of 50 microns. This photoconductive member was used together with an intermediate record member described in Example 13 and a commercially available electrostatic recording paper in the process illustrated in FIG. 16. In the initial step shown in FIG. 16a, a platinum wire 0.08 mm. thick was used to charge the photoconductive member uniformly from a DC supply of +6,000 volts, and a photographic enlarging device was used in the subsequent imagewise exposure (FIG. 16b) for one second and with maximum illumination of 20 luxes on the image surface. The transfer to the intermediate record member was effected (FIG. 16c) by application of +1,100 volts to the photoconductive member. Finally a voltage of -820 volts was applied to the upper electrode 8 (FIG. 16d) to transfer the latent image onto the recording paper. In this Example, electrodes 8 were conductive rubber sheets of 1 cm. in thickness and having hardness of 30 (JIS), and the pressure applied was 1 kg./cm². The latent image obtained on the recording paper was developed by a magnetic brush and proved satisfactory.

EXAMPLE 15

On an aluminium plate 1 mm. thick was evaporated amorphous selenium to a thickness of 100 microns to provide a radiation sensitive member, which was used in the process illustrated in FIG. 15 together with an intermediate record member described in Example 13 and a commercially available electrostatic recording paper. In the initial step of FIG. 15a, an X-ray was used as radiation at a maximum rate of dosage of 450 mr./sec. measured on the surface of the radiation sensitive member, and a positive voltage of +1,450 volts was applied to the latter. In the second step, a negative voltage of -820 volts was applied to the upper electrode 8. In both steps, the pressure applied was 1 kg./cm². An electrostatic image of good quality was obtained on the recording paper.

The intermediate record member and associated process mentioned above may be advantageously utilized to construct a copying machine. In this instance, it is desirable to have the intermediate record member in the form of an endless belt. Several embodiments of such copying machine will be described with reference to FIGS. 17 to 21, wherein like parts are designated by same reference numerals. Also in these Figures, for the convenience of description, the radiation sensitive member will be designated by numeral 55 on the understanding that it may comprise a substrate 56, a conductive layer 57 and a radiation sensitive layer 58 as shown in FIG. 15a or may comprise a conductive substrate 56 and a radiation sensitive layer 58 as shown in FIG. 16a. The intermediate record member will be designated by numeral 70 and can have various forms as shown in FIGS. 14a to 14d. However, in FIGS. 18 and 20, the member should have a conductive substrate or a conductive layer on the opposite surface to the mesh layer 72 for the purpose of applying the required voltage. Finally, a final record member will be designated by numeral 76, but it should be understood that it may not be provided with a conductive base 77 as shown in FIGS. 15b and thus may be constituted by an insulating recording layer alone.

Referring to FIG. 17, an original 80 to be reproduced is arranged fixedly in position and a movable light source 81 in the form of a pair of lamps is arranged to project the image of successive contiguous parts of the original through a movable op-

tical system 82 and a stationary slit member 83 onto the radiation sensitive member 55 in the form of a flat sheet that is arranged to move below the opening in the slit member 83. The radiation sensitive member 55 has its conductive layer connected with one terminal of a DC supply 9 through a slip ring and has its radiation sensitive layer facing downward. Immediately below the member 55 is arranged a cylindrical support 84 on which is tensioned the intermediate record member 70 with its mesh layer exposed externally. The support 84 is made from a conductive material and is earthed as shown. Thus the contact between the conductive layer or substrate of the intermediate record member 70 and the cylindrical support 84 provides an earth connection to this member. The support is rotatably carried on a shaft (not shown) which is supported by bearings 85. The bearings 85 are mounted to be vertically slidable by suitable means, and a cam plate 86 is arranged to contact the bearings. The arrangement is such that as the cam plate rotates by operation of a suitable drive therefor, the cylindrical support 84 is moved upwardly to urge the intermediate record member 70 thereon against the radiation sensitive member 55. Adjacent the support 84, there is provided a conductive roller electrode 8 which is shown to be electrically connected with another terminal of the supply 9. The supply has an earth terminal and thus is adapted to apply a positive voltage of selected magnitude to the radiation sensitive member 55 and to the final record member 76 in the form of a continuous web, respectively, the latter being supplied from a roll 87 of such member. The roller electrode 8 is positioned so that as the final record member 76 is moved past it, the member 76 is urged against the intermediate record member 70 on the cylindrical support 84. Forwardly of the electrode 8, as viewed in the direction of clockwise rotation of the support 84 indicated by an arrow, there is provided an eraser roller 88 for contact with the intermediate record member 70, and the eraser roller is connected with an AC source 89. Below the roller electrode 8 is provided a developing unit 90 and a guide roller 91 is arranged above the unit to move the final record member 76 partly dipped into the developing agent in the unit 90. Forwardly of the unit 90 along the path of movement of the member 76 indicated by an arrow, there is provided a fixing unit 92 which is arranged to move toward or away from the path of the record member 76 defined between the guide roller 91 and a pair of drive rollers 93. On the outlet side of the rollers 93 is provided a cutter 94.

In operation, before the optical system starts to scan the original 80, the cam plate 86 is operated to move the cylindrical support 84 upwardly, thereby bringing the members 55 and 70 into close contact. Then the light source 81, optical system 82, the radiation sensitive member 55, the intermediate record member 70 on the cylindrical support 84 and the final record member 76 are driven by synchronizing means to move at suitable speeds. At the same time, the light source 81 and the supply 9 are energized, and the fixing unit 92 is moved to its operative position in which it can serve to fix the developed image on the member 76. Then an electrostatic image of the original 80 is formed on the intermediate record member 70, transferred onto the final record member 76, developed by the unit 90, and fixed by the unit 92 and eventually the member 76 is cut to a predetermined length by the cutter 94 when the system 81, 82 has scanned to the right-hand end of the original. Thereupon, the cam plate 86 is operated to lower the support 84, and the light source 81, optical system 82 and the radiation sensitive member 55 are moved back to their original positions. At the same time, the fixing unit 92 is retracted. During the time when the support 84 is rotating clockwise, any residue of the latent image on the intermediate record member 70 is erased by the erasure roller 88. The latent image on the radiation sensitive member 55 (refer FIG. 15a) will have an attenuation time constant which is determined by the dark resistance and the electrostatic capacitance of the radiation sensitive layer. Usually such time constant is much longer than the exposure time, and when it is sufficiently short as compared with the period of one cycle of

the operation described above, the latent image will disappear by attenuation until the next cycle starts. However, where such time constant is comparable to the period of operation cycle, the reflector for the light source 81 may be provided with a slit 81' for allowing leakage of light therethrough which causes attenuation of the latent image thereon.

In FIG. 18, the copying machine shown is generally similar to that shown in FIG. 17 except that the intermediate record member 70 is in the form of an endless belt running around 10 three conductive rubber rollers 95 which form a triangle, and that another conductive roller electrode 8 is arranged to contact the inner conductive layer or substrate of the member 70 to provide an earth connection thereto. One of the rubber rollers 95 that is arranged directly below the slit member 83 is arranged to be slidably vertically by parts 85 and 86 for the purpose of urging the intermediate record member 70 against the radiation sensitive member 55 before these members are set in motion.

FIGS. 19a and 19b show another modification which is 20 similar to FIG. 18 in that the intermediate record member 70 is in the form of an endless belt running around three conductive rollers 8 which form a triangle. As shown, these rollers are earthed to provide an earth connection to the member 70. In 25 addition, the radiation sensitive member 55 is in the form of a hollow cylinder, within which an optical system comprising lens 82 and a pair of reflecting mirrors M₁, M₂ is partly received. Also the slit member 83 is arranged inside the cylinder member adjacent the inner wall thereof. The arrangement of the projection system is shown in detail in FIG. 19b. Thus the exposure of the radiation sensitive member 55 is 30 made from the interior of the cylindrical member 55, and at this end, it has a conductive transparent base 56 which is connected with one terminal of the DC supply.

35 The projection system is arranged such that the mirror M₂ and the slit member 83 remain stationary when the cylinder member 55 rotates, but the lens 82 and the mirror M₁ move to the right, as viewed in FIG. 19a, as indicated by an arrow. It 40 will be appreciated that in operation the members 55, 70 and 76 are driven to move at the same linear speed, while the light source 81, the lens 82 and the mirror M₁ are driven in synchronism, but at predetermined speeds. After the original 45 80 has been scanned, the light source 81, the lens 82 and the mirror M₁ return to their original positions. Because the radiation sensitive member is a rotating cylinder, there is no need to provide parts 85, 86 shown in FIGS. 17 and 18.

To provide proper attenuation to the latent image on the radiation sensitive member, there is provided a light inlet 96 (FIG. 19a).

50 FIG. 20 shows a further modification in which the radiation sensitive member 55 is of cylindrical form as shown in FIG. 19a and the intermediate record member 70 is an endless belt running around a pair of conductive roller electrodes 8 which 55 are earthed. The member 70 is made from transparent material and the member 55 need not be transparent. Thus the substrate of the member 55 may be made from metal, for example. A pair of further rollers 97 made from conductive rubber are arranged, fixedly in position, to press the lower span of the member 70 against the member 55 from above. These rollers 60 97 are mechanically and electrically interconnected and are earthed as shown. The space between the rollers 97 provides a slit for projection purpose. In this instance, the original 80 is moved in the direction shown by an arrow, and thus the light source 81 and the optical system 82 remain stationary. The members 70, 55 and 76 are driven at the same linear speeds as 65 before.

70 While the embodiments shown in FIGS. 17 to 20 operate on the principle shown in FIGS. 15a and 15b, FIG. 21 illustrates a copying machine which embodies the principle of FIGS. 16a to 16d. The radiation sensitive member 55 is formed as a rotatable cylinder, and the intermediate record member 70 is an endless belt running around three conductive roller electrodes 8. The projection system is substantially similar to FIGS. 17 and 18 and the interlocking mechanism between the

members is similar to FIG. 19a. However, there is provided a charger 65 (FIG. 16a), which is connected to a DC supply 9' of high voltage for uniformly charging the radiation sensitive member 55 by corona discharge before it is subjected to imagewise exposure through the slit member 83. The exposure forms a latent image on the member 55, which latent image is transferred onto the intermediate record member 70 and finally transferred onto the member 76.

What is claimed is:

1. An electrophotographic process for inducing an electrostatic latent image on an insulating record member comprising the steps of placing the insulating record member in face-to-face contact with a normally insulating and radiation sensitive member which has a radiation sensitive layer, which layer becomes conductive upon exposure to radiation, exposing said radiation sensitive member to radiation to form a latent image thereon either before or after contacting said members, said radiation sensitive layer having an insulating layer of a mesh pattern, said insulating mesh layer abutting against the said record member when said members are placed in contact with each other, and applying a voltage across said members to charge the record member in accordance with said latent image in areas opposite to exposed areas of the radiation sensitive member which have been subjected to radiation.

2. An electrophotographic process according to claim 1 wherein said mesh layer has a thickness from 0.5 to 100 microns, a resistivity not less than $10^9 \Omega \text{cm}$. and surface resistance not less than $10^9 \Omega$ per square.

3. An electrophotographic process according to claim 1, in which said member for receiving and transferring an image is previously formed with an electrostatic latent image hereon, and then transferring the preformed image onto the record member upon application of the voltage across the members while being held in contact.

4. An electrophotographic process according to claim 1 further comprising the step of subjecting said radiation sensitive layer to imagewise exposure during the step of applying the said voltage to form the said latent image to be transferred to said insulating record member.

5. An electrophotographic process for inducing an electrostatic latent image on an insulating record member which has an insulating recording layer and an insulating surface layer which surface layer comprises a mesh pattern comprising the steps of placing said record member in face-to-face contact with a radiation sensitive member which has a radiation sensitive layer, said radiation sensitive layer becoming conductive upon exposure to radiation, exposing said radiation sensitive layer to radiation to form a latent image thereon either before or after contacting said members, said insulating mesh layer being maintained between the said contacted members, and applying a voltage across said members to charge the insulating record member in accordance with said latent image in

areas opposite to the radiated areas of the radiation sensitive layer.

6. An electrophotographic process according to claim 5, wherein said mesh layer has a thickness from 0.5 to 100 microns, a resistivity not less than $10^9 \Omega \text{cm}$. and surface resistance not less than $10^9 \Omega$ per square.

7. An electrophotographic process according to claim 5 further comprising the step of subjecting said radiation sensitive layer to imagewise exposure during the step of applying the said voltage to form the said latent image to be transferred to said insulating record member.

8. An electrophotographic process for inducing an electrostatic latent image on an insulating record member comprising the steps of placing a radiation sensitive member, which

15 member becomes conductive upon exposure to radiation exposing said record sensitive member to radiation to form a latent image thereon after contacting said members in face-to-face contact with an insulating intermediate record member, the intermediate member having an insulating recording layer

20 and an insulating surface layer of a mesh pattern thereon, the insulating mesh layer abutting against the radiation sensitive member, applying a first voltage across said members to charge the intermediate record member in accordance with said latent image, placing the intermediate member in face-to-

25 face contact with a final record member such that the said mesh layer is sandwiched between the said intermediate and final record members to charge the final record member in accordance with the latent image on the intermediate record member.

9. An electrographic process for inducing an electrostatic latent image on at least one insulating record member comprising the steps of placing said insulating record member in face-to-face contact with a normally insulating member which member becomes conductive upon exposure to radiation, ex-

30 posing said member to radiation to form a latent image thereon either before or after contacting said members, forming a thin insulating layer having a mesh pattern on one of said members, maintaining said mesh between said contacted members and applying a voltage across said members to charge the insulating record member in accordance with latent image.

10. The electrophotographic process specified in claim 9 further comprising the steps of removing said applied voltage and shorting said members to retain the transferred image on said insulating record member.

11. The electrographic process as specified in claim 9 in which said member for receiving and transferring an image is previously formed with an electrophotographic process as specified in claim 9 in which said member for receiving and transferring an image is previously formed with an electro-

50 static latent image thereon.
